UNITED STATES PATENT OFFICE

95,741

DESIGN FOR A BARBECUE MACHINE CASING

Gus Garvis, Des Moines, Iowa

Application March 12, 1935, Serial No. 55,849

Term of patent 7 years

To all whom it may concern:

Be it known that I, Gus Garvis, a citizen of the United States and a resident of the city of Des Moines, county of Polk, and State of Iowa, have invented a certain new, original, and ornamental Design for a Barbecue Machine Casing, of which the following is a specification, reference being had to the accompanying drawing, forming part thereof:

I claim:

The ornamental design for a barbecue machine casing substantially as shown.

GUS GARVIS.
